OTHER PUBLICATIONS

Luo, "Electrical Connector Housing", U.S. Appl. No. 29/556,754, filed Mar. 3, 2016.

Primary Examiner — Angela J Lee

Assistant Examiner — Shawn T Gingrich

(74) *Attorney, Agent, or Firm* — Keating & Bennett, LLP

(57) **CLAIM**

The ornamental design for electrical connector housing, as shown and described.

DESCRIPTION

FIG. 1 is a top, front, and right side perspective view of an electrical connector housing for a two-by-ten contact array showing my new design;

FIG. 2 is a bottom, back, and right side perspective view thereof;

FIG. 3 is a top, front, and left side perspective view thereof;

FIG. 4 is a front view thereof;

FIG. 5 is a back view thereof;

FIG. 6 is a left side view thereof;

FIG. 7 is a right side view thereof;

FIG. 8 is a top view thereof;

FIG. 9 is a bottom plan thereof;

FIG. 10 is bottom and left side perspective view thereof;

FIG. 11 is a top, front, and right side perspective view of an electrical connector housing for a two-by-twenty contact array showing my new design;

FIG. 12 is a bottom, back, and right side perspective view thereof;

FIG. 13 is a top, front, and left side perspective view thereof;

FIG. 14 is a front view thereof;

FIG. 15 is a back view thereof;

FIG. 16 is a left side view thereof;

FIG. 17 is a right side view thereof;

FIG. 18 is a top view thereof;

FIG. 19 is a bottom plan thereof; and,

FIG. 20 is bottom and left side perspective view thereof.

The broken lines in the drawing illustrate portions of the electrical connector housing that form no part of the claimed design. The unshaded surfaces form no part of the claimed design.
